Inventor:
Charles R. Moore
by *S. W. Adams* Atty.

UNITED STATES PATENT OFFICE.

CHARLES R. MOORE, OF WYOMING, NEW JERSEY, ASSIGNOR TO WESTERN ELECTRIC COMPANY, INCORPORATED, OF NEW YORK, N. Y., A CORPORATION OF NEW YORK.

TELEPHONE TRANSMITTER.

Application filed April 22, 1924. Serial No. 708,116.

This invention relates to microphone transmitters, and more particularly to a type adapted for use in combination with a sensitive receiver for the purpose of aiding deaf persons to hear.

The object is to provide an instrument of this character which will be simple, compact, cheap to manufacture and efficient in use, having comparatively few parts which are assembled in such a manner as to be readily accessible for purpose of repair, adjustment or substitution of parts.

In accordance with this invention, the agitating member or diaphragm is made of insulating material and contacts with resistance varying material contained in depressions or cups formed at the junction point of a number of immovable electrodes and insulating material. The terminals of the transmitter are preferably secured to these electrodes. Due to this construction it is not necessary to attach leads to the agitating member or diaphragm, thereby permitting the diaphragm to move more accurately in accordance with its impressed frequencies.

Referring to the drawings, Fig. 1 is a front assembly view of the transmitter with a portion of the mouth piece and the diaphragm partially cut away and Fig. 2 is a sectional view thereof.

Similar reference characters refer to similar parts throughout the several views.

This transmitter generally consists of a casing 10 which may be of non-conducting material and in which concentrically arranged metallic electrodes 11 and 12 are secured by means of a number of screws such as 15 and 16 shown in Fig. 2.

The electrodes 11 and 12 are insulated from each other by means of a ring 13 interposed between the inner and outer electrodes and which may be made of any sort of well known insulating material such as mica or hard rubber. These electrodes are insulated from casing 10 by means of an insulating disc 14. Screws 16 are each provided for fastening the wire terminals 17 and 18 of the electrodes and are insulated from casing 10 by means of insulating bushings 19 and 20 respectively. The elec-

trodes 11 and 12 and insulating ring 13 are each provided with a number of registering recesses adapted to form a plurality of preferably semi-spherical shaped cups 21, 55 22, etc., which are each adapted to be filled with carbon granules as shown in Fig. 2.

On the edge of casing 10 and parallel to the plane surface of the electrodes there is mounted a diaphragm 23 which may be of 60 any suitable non-conducting material. This diaphragm is held in adjusted position in contact with the carbon granules in cups 21-22 etc., by means of the mouth piece 24 which is preferably made of insulating 65 material and screwed on the threaded ridge 25 of casing 10.

What is claimed is:

1. In a telephone transmitter, a structure comprising immovable concentric conducting sections separated by insulation and having depressions formed in said structure at the point of junction of said sections and insulation, a resistance varying medium in said depressions for bridging said insulation, and an agitating member of insulating material directly in contact with said resistance varying medium and spaced from all of said conducting sections.

2. In a telephone transmitter, a structure 80 comprising immovable concentric conducting sections separated by insulation, a resistance varying medium for bridging said insulation, and an agitating member of insulating material in contact with said resistance varying medium and spaced from said conducting sections.

3. In a telephone transmitter, a casing, a pair of immovable concentric electrodes mounted therein, a ring of insulation separating the same, said electrodes and ring having a number of depressions, at their junction point, carbon granules in said cups, a diaphragm of insulating material directly in contact with the carbon granules and spaced from both electrodes and a terminal mounted on each electrode.

4. In a telephone transmitter, the combination with a casing, a plurality of concentrically disposed immovable electrodes arranged in said casing, an insulating ring interposed between said electrodes, said elec-

trodes and ring forming depressions at their junction points, a resistance varying medium in said depressions for bridging said insulating ring, a disc associated with 5 said electrodes, and fastening means passing through said casing and disc and into said electrodes, said fastening means being

insulated from said casing and serving as terminals.

In witness whereof, I hereunto subscribe 10 my name this 16th day of April A. D., 1924.
1924.

CHARLES R. MOORE.
